UNITED STATES PATENT OFFICE.

JOHN J. WILLIAMSON, OF BOSTON, MASSACHUSETTS.

RUBBER BOOT.

SPECIFICATION forming part of Letters Patent No. 296,495, dated April 8, 1884.

Application filed July 28, 1883. (No model.)

To all whom it may concern:

Be it known that I, JOHN J. WILLIAMSON, of Boston, in the county of Suffolk and State of Massachusetts, a citizen of the United States, have invented a new and useful Improvement 5 in Rubber or Gum Boots, of which the following is a full, clear, and exact description, reference being had to the accompanying drawings, forming a part of this specification, in explaining its nature, in which—

Figure 1 represents a perspective view of a rubber boot containing my invention. Fig. 2 is a vertical section thereof; and Fig. 3 represents the boot with the leg folded down to 15 enable the foot to be inserted into the foot portion of the boot before the leg portion is drawn and fastened into position on the leg.

The object of this invention is a rubber or gum boot having a leg of light and flexible 20 material, and perfectly water-proof.

It is well known that the ordinary rubber or gum boot of the market has a stiff, inflexible leg of rubber or gum, of substantially the same thickness as the lower or foot portion of the 25 boot, and that this construction has been followed in order to make the leg stiff enough to stand. It is also well known that by making the leg in this way the boot is made very heavy and clumsy. There is also another style of rubber boot, made especially for ladies' wear, of a 30 lighter construction; but the leg portion of this boot is of the same thickness as the foot, and is much heavier than is necessary; and my invention is designed to obviate the objections 35 to these forms of boots, and at the same time cheapen their construction.

Referring to the drawings, A represents the foot portion of a rubber or gum boot, and B the leg. This portion, however, instead of being made of the same thickness as that of the 40 foot, or instead of being made heavy enough to stand alone, is constructed of a thin, flexible water-proof material, like gossamer rubber cloth, and preferably is of the general 45 shape and contour of the leg, and may be made of any desirable length. As, however, a boot-leg made from light pliable material of this nature will not stand or remain upright, it is necessary to provide means for fastening the 50 same to the leg to hold it in position, and for this purpose I use a strap, b, which is fastened at one end to the boot-leg, and passes through

a loop, d, also fastened to the boot, and having at its end a sliding buckle, c, which slides upon the strap to tighten or loosen it; or an 55 elastic strap may be led continuously around the upper section of the boot to embrace the leg; or a cord may be inserted in loops at the top in such a manner that its ends may be used to tighten the boot-leg; or a gore or lace opening may be made in the upper part of the leg, 60 and the boot-leg may be laced to the leg by a suitable laeing-cord; but I do confine myself to the especial method of fastening the boot-leg to the leg of the wearer, as there are many 65 other obvious ways of so doing, and for the purposes of the invention one is sufficient.

The boot-leg may be provided with elastic gores e at or near the ankle, to cause the boot to fit the foot tightly at the instep and lower portion of the leg.

I have described the leg as made of "gossamer" rubber cloth, which, technically, is a solarized fabric; but it may be of any light rubber or gum cloth, vulcanized or "mackintosh," or, indeed, of the water-proof "repellent" fabric, made with alumina salts or alumina soap, without departing from the essential spirit of the invention, which is to have the foot part of a rubber boot of the usual thickness and wearing quality and the leg part of a very light water-proof material, which may be, if desired, wrinkled down about the ankle or pulled up to protect the leg from wet.

In making the boot, when rubber, gossamer, 85 or other flexible material is used, the ordinary method of making rubber boots is employed, and the leg portion is separately formed and united to the foot portion by vulcanization; or, when a material is used for the boot-leg 90 which will not be damaged by heat, it may be united to the rubber or gum foot portion in the vulcanizing process, in which case the lower edge of the boot-leg should be frayed or provided with extensions, upon the inner and 95 outer surface of which the rubber can be vulcanized for the purpose of securing a strong union. The boot-leg may also be united to the foot portion by sewing, or in any other desirable way.

The light, pliable leg-section may have one or two seams—that is, it may be formed of one piece of material, in which case the seam may be upon one side or the back of the leg, or it

may be made of two pieces of material, much as the ordinary boot-leg is made; or it may be vulcanized to shape, in which case it will have no seam, but simply an opening at the top and 5 at the bottom, and the bottom will be shaped to adapt it to be vulcanized or otherwise fastened to the rubber or gum foot portion of the boot.

To put on the boot, it will be well to arrange 10 the leg as represented in Fig. 3—that is, to partly turn out the upper portion of the boot-leg to expose the inner section and the strap *f*, which is attached to the boot upon the inside just above the heel, by which the foot portion of the boot may be pulled on before the 15 leg is lifted into place. The boot-leg is then pulled up and adjusted upon the leg, and secured to the leg in any desirable way.

The advantages of this construction over the 20 old form of rubber boot are too apparent to need any further explanation.

Having thus fully described my invention, I claim and desire to secure by Letters Patent of the United States—

1. The combination, in a boot, of a rubber 25 foot portion, a thin, flexible leg, and the gores *c*, let into the lower portion of the leg, all substantially as and for the purposes described.

2. A rubber boot the foot part of which is of india-rubber compound of substantially the 30 usual thickness, and is adapted to be drawn upon the foot of the wearer without traction upon the leg part, and which has a closed leg part of gossamer or substantially similar thin rubber-cloth material, provided with means of 35 attachment to the leg or body of the wearer, substantially as described.

JNO. J. WILLIAMSON.

FRED. HARRIS.

It is hereby certified that in Letters Patent No. 296,495, granted April 8, 1884, upon the application of John J. Williamson, of Boston, Massachusetts, for an improvement in "Rubber Boots," an error appears in the printed specification requiring the following correction, viz: In line 63, page 1, between the words "do" and "confine" the word *not* should be read; and that the Letters Patent should be read with this correction therein to make it conform to the record of the case in the Patent Office.

Signed, countersigned, and sealed this 20th day of January, A. D. 1885.
